United States Patent Office

Des. 200,689
Patented Mar. 23, 1965

200,689

SIDEWALL

Timothy D. Calvin, Akron, Ohio, assignor to Bearfoot
Airway Corporation, Wadsworth, Ohio, a corporation of Ohio

Filed Apr. 15, 1964, Ser. No. 79,508

Term of patent 14 years

(Cl. D90—20)

FIG. 1

FIG. 3

FIG. 1 is a side elevation view of a sidewall showing my new design;

FIG. 2 is a fragmentary sectional view taken substantially on line 2—2 of FIG. 1; and

FIG. 3 is an enlarged fragmentary perspective view thereof.

The portions of a tire and trim ring shown in broken lines are included for illustrative purposes only.

I claim:

The ornamental design for a sidewall, substantially as shown and described.
